[57] ABSTRACT

An electromagnetic relay has a contact spring set in which the contact springs are held in fixed position between two plastic base members, one of which is thermoplastic and is secured to the other by deforming the thermoplastic material during heating by ultrasonic means. The contact springs are aligned in the correct position during assembly by means of registration surfaces mounted on the base member which is not deformed during assembly.

CONTACT SPRING SET FOR AN ELECTROMAGNETIC RELAY

BACKGROUND

1. Field of the Invention

The present invention relates to a contact set for an electromagnetic relay, and more particularly to such a contact set which is adapted for mechanized assembly.

2. Prior Art

Progress in the art of electromagnetic relays has led to the development of ever smaller and more compact arrangements, in which the magnetic system of the relay and the electrical conducting parts thereof are arranged as close to each other as possible. It has become common to mount the contact springs separately from the coil of the magnetic circuit, either to the side of the yoke of the magnet, or below it, and this arrangement is especially advantageous for use with relay constructions in which a minimum height is desired for the relay, as in so-called "card relays."

These relays, and miniature relays of other types, require very careful soldering in connecting the terminals of the relays, to protect the electrical contact springs of the relay from damage, as the terminals are located quite near to the contact springs. In order to furnish a measure of protection to the contact springs, the solder connections are sometimes passed through apertures in a separate base plate, formed of insulating material, and the soldering takes place on the opposite side of the plate from the contact springs. However, space around the edge of the apertures, allows contaminating vapors to pass through the apertures, which degrade the performance of the contact springs.

It has been proposed to employ a block of insulation material having recesses or chambers in which the contact springs are located, so that the operative parts of the contact springs are protected by being isolated from the solder terminals, and insulated from other conductive parts. For example, the German Gebrauchsmuster 6,601,156 illustrates a contact spring set having a single block of insulating material, provided for all of the contact springs, which are in the form of wire springs. In this arrangement, the contact springs are located in recesses in the block. However, this construction has the disadvantage that the correct placement of the contact springs during assembly of the relay is very difficult to mechanize.

SUMMARY OF THE INVENTION

It is a principal object of the present invention to provide a contact spring set for a relay having means for protecting the contact springs from damage during soldering, and for insulating the contact springs from the electrically conductive members.

Another object of the present invention is to provide such a contact spring set which is readily adaptable to being assembled and constructed by a highly mechanized process.

A further object of the present invention is to provide such a contact spring set in which the contact springs may be placed in position relative to an insulating-base member prior to assembly of the apparatus.

Another object of the present invention is to provide such a contact spring set in which only two insulating-

base members are required to form the complete spring set assembly.

A further object of the present invention is to provide such a contact spring set for automatically aligning the various components of the apparatus during assembly thereof.

Another object of the present invention is to provide such a contact spring set having means for rendering the spring contacts relatively insensitive to vibration.

Other objects and advantages of the present invention will become manifest upon an examination of the following description and the accompanying drawings.

In one embodiment of the present invention, there is provided a contact spring set including a block of insulating material formed of an upper base member and a lower base member, said contact springs being interposed between the two base members and fixed in position in relation to one of said base members.

BRIEF DESCRIPTION OF THE DRAWINGS

Reference will now be made to the accompanying drawings in which:

FIG. 1 is an end elevation view of an electromagnetic card relay having a contact spring set formed in accordance with an illustrative embodiment of the present invention;

FIG. 2 is a perspective view of a portion of the apparatus of FIG. 1;

FIG. 3 is an exploded perspective view of a portion of the apparatus illustrated in FIGS. 1 and 2, illustrating the manner of assembly of one of the contact springs;

FIG. 4 is a vertical cross sectional view of a portion of the apparatus illustrated in FIG. 3, when in assembled condition;

FIG. 5 is a vertical cross sectional view of the apparatus of FIG. 4, taken along the section line V—V;

FIG. 6 is an exploded perspective view of a portion of the apparatus of FIGS. 1 and 2, illustrating the manner of assembly of a second contact spring;

FIG. 7 is an exploded perspective view of a portion of the apparatus of FIGS. 1 and 2, illustrating the manner of assembly of a third contact spring;

FIG. 8 is a vertical cross sectional view of a portion of the apparatus illustrated in FIG. 7, after assembly; and

FIG. 9 is a horizontal cross sectional view of a portion of the apparatus illustrated in FIG. 8, taken along the section line IX—IX.

DESCRIPTION OF THE PREFERRED EMBODIMENTS

Referring now to FIG. 1, in which a so-called card relay is illustrated, the insulating block of the relay is made up of a lower base member 1 and an upper base member 2. The base members 1 and 2 are both formed of insulating material, and are assembled in such a way as to hold various contact springs 8, 9 and 10 in correct relationship, after assembly. The contact springs 8 and 9 are fixed contacts of the relay and the contact spring 10 is a movable contact spring, normally closing an electrical circuit with the upper contact spring 8, but opening that circuit and closing an electrical circuit with the contact spring 9, when the relay is operated.

60

65

A magnet system is provided for operation of the relay, and the magnet system incorporates a yoke 3, a coil 4 supported by the yoke 3, and an actuating member 5 having a depending projection 7. When the relay is actuated by passing a current through the coil 4, the actuating member 5 functions to lower the projection 7 against the free end of the contact spring 10, to change the position of the contact spring 10. The magnet system is typically a separate assembly, and is connected with the contact spring set by means of a bracket 6, adapted to engage notches 15 provided in opposite side portions of the base members 1 and 2, and held thereby when the magnet assembly and contact spring set are assembled.

As best shown in FIG. 2, the contact sets comprise two separate single pole double-throw switches, one being located on either side of the base members 1 and 2. The actuating member 5 is provided with two projections 7, one for each of the movable contact springs 10 and 10' of the two switches. As the two switches are identical, except for their position relative to the base members 1 and 2, the construction and operation of only one of the contact spring sets need be described in detail.

As best shown in FIG. 2, one of the contact spring sets is arranged in a recess 11 having a side wall defined by a side surface of the base members 1 and 2, and having lower and upper walls defined by a portion 1a of the lower base member 1 projecting outwardly below the recess 11, and a corresponding portion 2a of the upper base member 2 extending outwardly above the recess 11. The three contact springs 8, 9 and 10 have portions which are anchored between the base members 1 and 2, and are maintained in correct position thereby.

Each of the base members 1 and 2 are formed as a relatively flat plastic construction, having a central recess or aperture 12 designed to accommodate the magnetic coil 4. Each of the three contact springs 8, 9 and 10 have an individual terminal part 8a, 9a and 10a, by which electrical connections to the control springs may be made by soldering. As shown in FIG. 2, the contact-making part 8b of the upper contact spring is positioned at the upper portion of the recess 11, and the contact-making part 9b of the contact spring 9 is positioned directly therebelow. The contact-making part 10b of the contact spring 10 is positioned between the contact-making parts of the contact springs 8 and 9, and is adapted to make electrical contact with one or the other in accordance with the condition of the actuating member 5. The recess 11 may be referred to as a circuit chamber, since it is isolated from the magnet assembly by the overlying portion of the upper base member 2, and isolated from the terminal parts 8a, 9a and 10a by the underlying portion of the lower base member 1.

The lower base member 1 is formed of a plastic material having a relatively high melting point, in order to provide mechanical integrity at the time heat is applied to the upper base member during assembly. The upper base member is formed of thermoplastic material so that application of heat thereto results in a softening and deforming of the plastic material. As the upper base member 2 is softened, it is brought into position in relation to the lower base member 1, securing the various contact springs 8, 9 and 10 in their correct positions in a manner described hereinafter. The lower base member 1 is not softened during such heating, and so

its surfaces do not undergo any change during assembly. The lower base member 1 may be formed of thermoplastic material having a higher melting point than that of the upper base member 2, or, alternatively, may be formed of thermosetting material, or the like.

The lower surface of the portion 2a of the upper base member 2 is provided with a recess 14 located directly above the contact-making part of the contact spring 8, and a corresponding recess 13 is provided in the upper surface of the portion 1a at a position underlying the contact-making part of the lower contact spring 9. The recesses 13 and 14 permit the outer ends of the stationary contact springs 8 and 9 to remain out of direct contact with the insulating base members 1 and 2, and the contacts are thereby made less vulnerable to mechanical vibrations transmitted through the base members 1 and 2.

Referring to FIG. 3, an exploded view of a contact spring 19 is illustrated, in association with cooperating portions of the lower base member 1 and the upper base member 2. The contact spring 19 corresponds to the contact spring 9 shown in FIGS. 1 and 2, but is formed in a slightly different shape than that shown in FIG. 2. The spring 19 has, at one end, a contact-making part 19b, and at the other end is connected to a vertically extending terminal part 19a. The horizontal part of the spring 19 is joined to the terminal part 19a by a vertically disposed part 19d, having a plurality of upwardly extending tabs 19c. During assembly, the terminal part 19a is lowered through a window 16 provided in the lower base member 1, until the horizontal part of the spring 19 has been lowered into contact with a horizontal supporting surface 17 provided on the lower base member 1. The position of the surface 17 is controlled with great precision during manufacture of the member 1, so that any manufacturing variations in the size and shape of the spring 19 do not affect the positioning of the horizontal part of the spring 19.

During assembly, the upper base member 2 is lowered into association with the lower base member 1, and a wedge-shaped nose member 21 glides downwardly along the terminal part 19a, bearing against a side edge of the window 16, and pressing the terminal part 19a and the vertically extending part 19d firmly against the inside surface of a wall 22 formed on the base member 1. The position of this surface of the wall 22 is controlled with precision during manufacture, so that the contact spring 19 is correctly positioned when the vertically extending part 19d lies against it.

Final assembly of the upper and lower base members 1 and 2 takes place by means of ultrasonic stapling, in which the upper base member 2 is pressed downwardly against the lower base member 1 and is deformed by heat generated by the application of ultrasonic sound thereto until the correct assembled condition has been reached. In this process, the nose 21 is simultaneously pressed downwardly into the window 16 and deformed in such a way as to tightly close the window 16, enveloping the upper portion of the terminal part 19a, and forming an impermeable barrier between the contact spring 19 and the terminal part 19a, where the soldering takes place. Simultaneously, during assembly, the two upwardly directed tabs 19c are pressed into the thermoplastic upper base member 2 and are thus held rigidly in association therewith after the upper base member 2 hardens on cooling. The amount of protrusion of the tabs 19c into the upper base member 2 is not

critical and, therefore, a very loose tolerance over the size and position of the tabs 19c may be allowed.

During assembly, a peg 22 provided on the upper base member 2 is inserted into an aperture 23 in the lower base member 1, and the lower end of the peg 22 is deformed into the shape of a rivet head adjacent the lower end of the aperture 23, to hold the base members 1 and 2 firmly together.

FIGS. 4 and 5 show, in two vertical sections which are perpendicular to each other, the cooperation of the contact spring 19 with the associated components of the assembly. The surface 17 supports, the horizontal part of the contact spring 19, and the cooperation of the upwardly extending tabs 19c with the upper base member 2 is illustrated. The deformation of the nose 21, in a manner such as to fill the window 16, is also illustrated in FIG. 4. The lower edge of the part 19d is supported by the surface 24 of the lower base member 1, as best illustrated in FIG. 5.

FIG. 6 illustrates, in exploded perspective view, the manner in which the contact spring 8 is assembled in relation to the lower base member 1 and the upper base member 2. The contact spring 8 incorporates a contact-making part 8b at one end thereof and a downwardly depending terminal part 8a at the other end thereof. The terminal part 8a is adapted to be inserted downwardly through a window 25 provided in the lower base member 1, so that the horizontal portion of the contact spring 8 is supported on a horizontal surface 30, formed as the upper surface of a wall 27. A deformable nose 26, depending from the upper base member 2, is aligned with the window 25 and urges the contact spring 8 into firm association with the outer surface of the wall 27 during assembly. A peg 28, provided on the upper base member 2, is received in an aperture 29, and the lower end of the peg is deformed to form a rivet head when assembly is complete.

The position of the surface 30 is controlled with great precision during manufacture of the base member 1. A plurality of depending noses 31 are provided extending downwardly from the upper base member 2 and are adapted to urge the contact spring 8 against the surface 30. The noses 31 may be formed without any particular tolerance since they are softened and deformed as much as necessary during assembly. After hardening and cooling, they function to maintain the contact spring 8 in position against the surface 30.

FIG. 7 illustrates, in exploded perspective view, the manner in which the contact spring 10 is assembled in association with the lower and upper base members 1 and 2. The contact spring 10 is formed with a free end as illustrated in FIGS. 1 and 2, for cooperation with the depending projection 7 of the actuating member 5, and has a depending terminal part 10a secured to the other end. The terminal part 10a is adapted to pass downwardly through a window 32 provided in the lower base portion 1, until the middle portion of the spring contact 10 is brought into contact with an inclined surface 35, provided on the base member 1. A shoulder 33 is provided adjacent the surface 35 on one side thereof, and an upwardly extending projection 34 is provided on the surface 35 on the opposite side of the contact spring 10 from the shoulder 33. The shoulder 33 and the projection 34 together serve to maintain the contact spring 10 in the proper position prior to assembly of the base members 1 and 2.

The upper base member 2 has an inclined surface 36, corresponding to the surface 35, and a pair of ribs 40 provided on the surface 36 are adapted to push the contact spring 10 firmly into contact with the surface 35 during, and after, assembly.

During assembly, a peg 37, provided on the upper base portion 2, is lowered into an aperture 39 provided in the lower base portion 1, and the end thereof is softened to form a rivet head. The peg 37 has a conical portion 38 at its base, adjacent the surface 36, and the portion 38 is adapted to be softened during assembly and to be squeezed between the surfaces 35 and 36, outwardly from the peg 37, and against an arcuate notch 10c provided in an edge of the contact spring 10, forcing the contact spring 10 into aligned relationship against the shoulder 33. In this manner, correct alignment of the contact spring 10 is assured during assembly. The position of the shoulder 33, as well as the position of the surface 35, are accurately controlled during manufacture of the lower base portion 1. During assembly, the ribs 40 are softened and deformed as required, but upon hardening, function to maintain the spring 10 in position against the surface 35.

FIGS. 8 and 9 show two vertical cross sectional views 25 showing the association of the contact spring 10 with the other elements of the assembly. FIG. 9 illustrates how the conical portion 38 of the peg 37 has been urged against the spring 10 to force it into juxtaposition with the shoulder 33. FIG. 8 illustrates the manner in 30 in which the rivet head 37a is formed at the lower end of the peg 37. A counterbore is provided in the lower portion of the aperture 39, to provide a shoulder maintaining the expanded rivet head 37a in position after assembly.

It will be appreciated from the foregoing that an easy tolerance is provided in many of the dimensions of the electrical contact springs, as well as in the manufacture of the upper base portion 2. All of the critical surfaces are provided on the lower base portion 1, so that this part alone must be made with precision. In addition, the manner in which portions of the upper base member are softened during assembly and urged into contact with the various contact springs so as to urge them into alignment with the registration surfaces on the base member 1, permits the formation of a contact set with contact springs which are highly accurate in their positioning, even though no special measures are taken to insure their alignment during assembly, other than simply inserting the terminal parts into the appropriate windows of the base member 1, and then pressing the base member 2 into association with the lower base member 1. It can thus be seen that the present invention lends itself to a high degree of mechanization, and may be readily and inexpensively assembled in large quantities.

In addition to the features described hereinabove, the assembled base formed of the members 1 and 2 may also be provided with further recesses, projections and the like, for the provision of other components such as a grounding spring or a relay protection cap. The nose 41 illustrated in FIG. 8 is, for example, provided for the purpose of securing a protective cap (not shown) in position.

Although the present invention has been specifically described in terms of a card-type relay, those skilled in the art will appreciate that it is not so limited, but may equally well be used with other relay constructions. In

addition the present invention may be employed in the manufacture of other assemblies in order to provide an efficient and highly accurate assembly process, which is highly adaptable to being mechanized.

What is claimed is:

1. A contact spring set for an electromagnetic relay comprising a plurality of electrical contact elements, and a block formed of insulating material and comprising first and second insulating members adapted to support said contact elements, said first insulating member being formed of thermoplastic material and said second insulating member being formed of an inherently stable plastic material, said block having a recess formed therein, said electrical contact elements having their contact-making parts supported within said recess, one of said contact elements having a portion interposed between said two insulating members, said two insulating members bearing against said one contact element to maintain it in fixed position relative to said second member.

2. Apparatus according to claim 1, including a plurality of movable contact elements, said movable contact elements being mounted on said block so that the motion of such movable elements defines a pair of spaced parallel planes.

3. Apparatus according to claim 1, wherein said contact elements each have a portion interposed between said two interlocked members.

4. Apparatus according to claim 1 wherein said inherently stable member is provided with means for supporting said contact elements.

5. Apparatus according to claim 4 wherein said contact elements are pressed against said supporting means by first insulating projections formed integrally with said deformable member.

6. Apparatus according to claim 1 wherein said two members are interlocked by means of a riveted peg formed integrally with one of said members and received in an aperture provided in the other of said members.

7. Apparatus according to claim 1 including a terminal connected with said one contact element and adapted to be soldered to an electrical conductor, said terminal extending through an aperture in one of said members.

8. Apparatus according to claim 7 wherein said aperture is closed by a deformable portion of said other

member.

9. Apparatus according to claim 7 wherein all of said contact elements comprise electrically conductive springs interposed between said two members and terminal elements for each of said springs extending at an angle to said springs through apertures in said one member.

10. Apparatus according to claim 1 wherein the contact-making parts of said contact elements are spaced from said block.

11. Apparatus according to claim 1 including a movable contact spring mounted between inclined supporting surfaces disposed on said two members.

12. Apparatus according to claim 1 including means for urging one of said contact elements laterally against a supporting wall formed integrally with one of said members by a projection formed integrally with the other said member.

13. Apparatus according to claim 1 wherein said one contact element has a plurality of projections, said projections being adapted to enter one of said members during assembly of said one member with said other member.

14. Apparatus according to claim 1 including means formed integrally with one of said members for supporting all of said contact elements preparatory to assembling said two members together.

15. A method for the production of a contact spring set, including the steps of providing first and second insulating members adapted to be interlocked to form a complete contact set assembly, providing a plurality of accurately positioned surfaces on said first member, placing a plurality of contact elements on said accurately positioned surfaces, superposing said second member over said contact elements, and securing said first and second members in fixed relation by each other by deforming said second member.

16. The method according to claim 15 including the step of deforming a projection integral with said second insulating member without deforming said second member as said projection is urged against a contact member.

17. The method according to claim 16 wherein said deforming takes place during heating resulting from the application of ultrasonic energy to said second member.
